Inventor:

L. M. Osborn.

UNITED STATES PATENT OFFICE.

L. M. OSBORN, OF HAMILTON, NEW YORK.

IMPROVED MILL-PICK.

Specification forming part of Letters Patent No. 40,183, dated October 6, 1863.

To all whom it may concern:

Be it known that I, L. M. OSBORN, of Hamilton, in the county of Madison and State of New York, have invented certain new and useful Improvements in Mill-Picks; and I do hereby declare that the following is a full, clear, and exact description of the same, reference being had to the accompanying drawings, and to the letters of reference marked thereon, making a part of this specification, in which—

Figure 1 is a transverse or sectional view of the entire pick. Fig. 2 is a perspective view of the head. Fig. 3 represents the blade; Fig. 4, the spring-plate.

Similar letters of reference denote like parts in all the figures.

To enable others skilled in the art to fully understand and construct my invention, I will proceed to describe it.

My improvement consists in a new and useful mode of supporting the blade or blades in the head of a mill-pick by means of a rigid and a yielding support acting in conjunction, and also in a new and useful mode of supporting the blades at any desired distance from the center of the head by means of notches, or their equivalents, and a suitably-formed head on the blade, &c.

A A, Figs. 1 and 2, represent the head, which may be made of cast-metal, and B B a yielding spring.

K represents the blade, which should be constructed of cast-steel.

The handle is shown at G. Through said handle is a rod, E. Said rod is provided with a nut, L, and a cap, F.

H represents a tenon, and i i shoulders resting against the spring k.

Letters D represent a series of notches or depressions suitably formed to receive the head of the blade K.

M M represent lips or sides, between which the spring B is placed.

When the above-described parts are arranged in the order shown in Fig. 1, the blades may be held in position by turning the nut L.

Having thus described my invention, what I claim as new, and desire to secure by Letters Patent, is—

1. A rigid support, with lips or sides, in combination with a yielding support, substantially as described.

2. A series of notches or indentations, substantially as described, or their equivalent, for the purpose of holding the blade at any desired distance from the center of the head, as set forth.

L. M. OSBORN.
